UNITED STATES PATENT OFFICE.

CHARLES R. KEERAN, OF CHICAGO, ILLINOIS, ASSIGNOR, BY MESNE ASSIGNMENTS, TO AUTOPOINT MANUFACTURING COMPANY, OF CHICAGO, ILLINOIS, A CORPORATION OF ILLINOIS.

PENCIL.

Application filed August 23, 1920. Serial No. 405,212.

To all whom it may concern:

Be it known that I, CHARLES R. KEERAN, a citizen of the United States, residing at Chicago, in the county of Cook and State of Illinois, have invented certain new and useful Improvements in Pencils, of which the following is a specification.

This invention relates to a pencil equipped with propelling mechanism interiorly of its body, and operable by means exteriorly thereof, for advancing into operative position a lead at one end, and an eraser at the other. In many respects the present pencil follows the construction already disclosed 10 in my application now pending as Serial No. 291,494 (Patent No. 1,372,296); it exhibits however, certain improvements which have to do particularly with a magazine within the pencil for the accommodation of reserve leads. It is to be understood, therefore, that the present pencil embodies a 15 number of features claimed in the applications aforesaid, as well as certain other improvements to which specific reference will 20 hereinafter be made.

In the accompanying drawing, an exemplification of this invention is shown in the manner following:

Figure 1 is a longitudinal section through 30 a tubular pencil body, certain of the interior parts being shown in elevation;

Fig. 2 is a similar view, enlarged, through the upper portion of the pencil;

Fig. 3 is a transverse section taken on line 35 3-3 of Fig. 2;

Fig. 4 is an elevation of the magazine member removed from the pencil;

Fig. 5 is a fragmentary view in longitudinal section of the sleeve which is arranged in the lower end of the pencil; and

Fig. 6 is a view in plan of one of the sections composing a magazine member of construction slightly different from that elsewhere exhibited.

In the use that is herein made of the terms "upper" and "lower," it is to be understood that I am referring to the pencil as it is pointed in use—that is, with the eraser end up, and the writing end down.

In Fig. 1 the pencil body, designated as A, is provided with a lower end 10 which terminates bluntly in the form of a truncated cone. In the construction shown, this body may be produced from metal in tubular formation so as to provide a casing within

which are accommodated the operating parts, as well as reserve leads. Arranged centrally within the body is a tube 11 that is deformed throughout its lower portion 12 to present a cross section other than round. At 60 its lower extremity this tube is shown to be formed with threads 13 which connect with a bushing 14 which may be sweated or soldered within the casing near its tip end. The walls of the casing at its lower extremity 65 are formed as at 15 to provide a constricted passage through which a lead is projected for use.

Surrounding the lower portion of the tube 11 is a sleeve 16 whose lower end is rested 70 upon the bushing. A plate 17 in the form of a washer is adapted to rest upon the upper end of the sleeve, or this end of the sleeve may be flanged as at 18, (see Fig. 5) so as to constitute a base for the reserve lead 75 magazine which, in the construction shown, is disposed throughout the upper region of the pencil within the annular space intervening between the walls of the casing and the tube 11. This space is subdivided by an 80 elongated magazine member B formed preferably in three sections, each of spring material in sheet form and each designed to remain in place under the influence of its own spring action. Each of these spring 85 sections comprises a radial arm 20 which is bent upon itself at its inner edge, as at 21, an arc-shaped wall 22 extending between the two bends. The wall 22 stands out from the central tube 11 the requisite distance to leave 90 a space within the magazine which may receive leads C without permitting motion thereof toward and from the pencil center. As shown in Fig. 3 this correct positioning of the arc-shaped wall is obtained by the 95 double bending at 21 so as to present the central curved section 23 in spaced relation to the central tube. A modified construction such as is shown in Fig. 6 is also suggested wherein each section of the magazine 100 member is provided at its lower end with a transversely disposed lip 24 extending between the arms 22 so as to constitute a base for the reserve leads which are accommodated within the pencil.

The upper end of the magazine member is represented as terminating slightly below the upper end 25 of the pencil body. A bushing 26 is secured non-rotatably to the tube 11, as by sweating or solder, immedi-

ately above the magazine member, and the tube extremity is further spun out at 27 to overlie this bushing so as to retain the same in place. Through the medium of threads 5 formed exteriorly on the bushing a connection is established with another bushing 28 that is secured interiorly of a collar 29 which in turn is rotatably connected with an eraser sleeve 30, these two parts— 10 the collar and eraser sleeve—constituting a head which is detachably secured to the pencil body in the manner explained. The bushing 26 serves, therefore, as a connecting medium for the head and also as a lock for 15 the three sections of the magazine member whose upper ends are engaged thereby. The propelling means for the lead which is actuated by the rotation of the eraser sleeve need not be described in detail.

20 According to the invention that I have herein described, the parts which form the magazine of this pencil may be very accurately and expeditiously produced. Their assembly into the pencil may also be accomplished with ease and precision. The construction is such as to provide for a number 25 of compartments each of which may accommodate a desired number of reserve leads in such a manner as to prevent undue motion therein. No shoulder or other element projects 30 interiorly from the casing at its upper end to interfere in the least with the removal or insertion of these leads. Furthermore, it will be noted that the connection between 35 the pencil head and body is one which may be very readily disestablished so as to permit a single lead to be removed for purpose of insertion within the central tube 11 wherein propulsion is effected.

40 I claim:

1. A pencil having a hollow casing for its body, a tube arranged longitudinally therewithin and secured thereto at its lower end, a transversely disposed arranged plate between the tube and casing, means for supporting the plate on its under side comprising a sleeve surrounding the tube and extending between the plate and the connection at the lower end of the pencil between 45 the tube and casing, a magazine member surrounding the tube extending above the plate, and a closure for the magazine adapt-

ed for detachable connection with the upper end of the pencil, substantially as described.

2. A pencil having a hollow casing for its body, a tube arranged longitudinally therewithin, there being an annular space between the tube and casing, and means subdividing said space comprising a plurality of sheet metal partition members, each formed to present two walls extending radially from the casing to the tube and bent upon themselves and then connected by an arc-shaped wall which lies adjacent the tube but spaced therefrom sufficiently to present its outer face from the casing wall a radial distance substantially equal to the diameter of a reserve lead to be accommodated within the subdivided space, the radial walls of the partition member being spring pressed against one another so as to remain in place of their own accord, substantially as described.

3. A pencil having a hollow casing for its body, a tube arranged longitudinally therewithin, there being an annular space between the tube and casing, and means subdividing said space comprising a plurality of sheet metal partition members, each formed to present two walls extending radially from the casing to the tube and then connected by an arc-shaped wall which lies adjacent the tube, the radial walls of the partition members being spring pressed against one another so as to remain in place of their own accord, substantially as described.

4. A pencil having a hollow casing for its body, a tube arranged longitudinally therewithin and adapted to guide the lead through the pencil, a connection between the tube and the body at the lower end of the pencil, a sleeve surrounding the tube and presenting its lower end adjacent said connection, means at the upper sleeve end affording a base for a magazine within the body, a magazine member surrounding the tube and extending above the magazine base, and a closure for the magazine adapted for detachable connection with the upper end of the pencil, substantially as described.

CHARLES R. KEERAN.
